MATERIAL AND PROCESS FOR OBTAINING METAL PRINTING PLATES WITH SILVER HALIDE EMULSIONS

Charles Edmund Meulendyke, Rochester, N. Y.

Application June 7, 1939, Serial No. 277,843

6 Claims. (Cl. 95—5.7)

This invention relates to the preparation of metallic sheets supporting colloid layers containing a sensitive silver salt and to the subsequent processing of such sheets into relief, planographic and intaglio plates for monochrome 5 and polychrome printing.

Reference is made to the previous state of the art in which an inert metallic layer supported on a metallic base serves to prevent contamination of a silver halide emulsion layer directly 10 coated on such inert layer. After processing the emulsion layer into a relief such colloid layer serves as a resist for the etching of the metal. There are, however, certain limitations and difficulties noted below in connection with this 15 method. Reference is also made to the previous state of the art in which a lacquer or varnish layer is employed in lieu of the inert metallic layer. Such lacquer layer serves to isolate the 20 emulsion layer from the contamination of a zinc or copper base, and to form a lacquer resist for the etching of the metal. The present invention proposes a material whose essentially novel and useful feature is its inclusion of both a metallic 25 and a lacquer interlayer in place of the single metallic or single lacquer layer hitherto employed. Such material constitutes an entity in itself creating new advantages and improvements and functioning novelly with respect to 30 any previous use of the single layers.

The material consisting of a metallic base plated with an inert metallic layer directly supporting a silver halide emulsion has disadvantages in that there is little choice of metal in forming the inert metallic interlayer and in that it is difficult to plate a perfect layer of metal non-contaminating to the emulsion layer. In fact, while zinc has been generally recognized as a most useful metal base for making line 35 cuts, such an accomplishment as a nickel-plated zinc which will not contaminate a silver halide emulsion coated directly thereon, has not been proven as practically attainable. Then again it is difficult to process a resist from a silver halide 40 emulsion layer which will withstand the etching medium. The use of mineral acids is out of the question and even a comparatively harmless etching medium such as ferric chloride tends to destroy such resist before satisfactory etching 45 depth has been reached. In fact ferric chloride in high concentration seems to be the only etchant which can be used with a silver halide emulsion resist. On the other hand there are certain advantages in the etching of a metal plate consisting of a basic metal sheet plated with a 50

metallic layer differently composed with respect to such base. An example is a copper sheet electroplated with a nickel layer. Now in the etching of a copper or a zinc plate as ordinarily carried out to form a half-tone or line cut, as depth 5 of etching is attained there is also a strong etching action on the sides of the depressions. This requires a skilled etcher who may etch in stages or may powder the sides of the depressions in order to form the correct sizes of dots or widths 10 of lines. With suitable choice of electroplated metal and suitable choice of etchant I have found that the etching operation can be made simple, in part due to the fact that the metal caps formed after cutting through the metallic interlayer tend to preserve the sizes of the original half-tone dots while permitting deep etching 15 into the metal base. This condition can be realized by use of a single etching solution which dissolves the metal of the base somewhat faster 20 than the metal of the interlayer. On the other hand, the metal of the interlayer can be purposely undercut and later such undercutting corrected in a second etching solution which dissolves the metal of the interlayer faster than 25 the base metal. For example, in the etching of nickel-plated copper supporting suitable local resists, and with judicious use of ferric chloride and cupric chloride as etching media as described in copending patent application (U. S. 30 Serial Number 275,514, filed May 24, 1939) the sizes of the dots, the slope of the sides of the dots and depth of etching can be simply controlled without the need of a skilled etcher. This reference shows how etching control is 35 established by use of etchants which differentially control the rates of etching of the two metals, and how nickel and copper can be etched at equal rates or either one faster than the other. My use of the lacquer layer to form a secondary 40 resist permits use of etchants which would destroy a silver halide emulsion resist. Properly speaking I do not use the metallic layer as a metallic resist, but rather as an etching-control layer. It is the varnish layer which functions as 45 the resist. The metallic interlayer etches only where unprotected by such resist. The etching operation can be said to be performed under the joint selective control of the lacquer resist and the metallic interlayer. 50

I believe I am the first to propose a material consisting of a basic metallic sheet whose surface is plated with a metallic layer suitably composed to function as an etching-control layer and supporting a lacquer or varnish layer which

in turn supports a colloid layer containing a sensitive silver salt. I believe I am the first to propose the inclusion of nickel-plated copper or nickel-plated zinc in such material. I preferably use a simple form of metallic interlayer although it can be plated as an alloy or even as a multiple-plated layer of different metals. I believe I am the first to propose the processing of such a material into a photomechanical printing plate. It is of course unnecessary that the plated metallic layer shall be truly inert to the silver halide emulsion, although I preferably use a metallic interlayer of such metals as silver, nickel or chromium which per se are inert to a silver halide emulsion. Such inert metallic layer together with the lacquer layer has the added advantage of affording a double protection to the emulsion from contamination by the metal base. The metallic layer primarily furnishes etching control and a hard printing surface while the lacquer layer furnishes a hardy resist and an inert layer between the metal and the emulsion.

I have found the cellulosic lacquers do not adhere strongly to metal, while gum lacquers tend to adhere very strongly. I have further found that gum lacquers tend to be attacked by the solutions used to process the colloid relief from the silver halide emulsion layer, while cellulosic lacquers are markedly resistant in this respect. For these reasons I suggest a mixed lacquer containing cellulosic and gum ingredients. Preferably I coat a gum lacquer such as shellac directly upon the metallic layer and then a cellulosic lacquer over this gum lacquer. However, I do not restrict myself in the choice of a lacquer or varnish and within the meaning of this invention I intend to include any suitable form such as cellulose nitrate, cellulose acetate, natural gums such as shellac, dammar and dragon's blood, as well as synthetic resins, all of which can be dissolved in appropriate organic solvents for application to the metallic surfaces. Also a suitable dye may be added to the lacquer layer to render it more visible or to prevent halation from the metallic surface. After formation of the emulsion relief the bared lacquer surfaces can be cut through to form bared metallic surfaces by brushing with a suitable organic solvent.

It will thus be seen that I have described materials and processes with all necessary details embodying the principles and attaining the objects and advantages of the invention. Since many manners of treatment, manipulation, selection and proportion of ingredients, succession of steps and other details may be variously modified without departing from the principles involved, I do not intend any limitation to such details excepting so far as set forth in the appended claims.

For the purpose of illustrating the several steps which can be followed in carrying out one form of the methods herein described and at the same time disclosing the material in one of its several forms, attention is called to the accompanying drawing in which:

Figure 1 shows a greatly enlarged section of a metallic base sheet 1, plated with a metallic layer 2 supporting a lacquer or varnish layer 3 which in turn supports a silver halide emulsion layer 4.

Figure 2 shows the emulsion layer as exposed under a half-tone screen and developed, exposed areas 5 being subsequently hardened.

Figure 3 shows the emulsion layer with the unexposed soluble areas washed out 6.

Figure 4 shows the lacquer dissolved out 7 exposing metal areas to be etched.

Figure 5 shows the plate etched through the metallic interlayer into the metallic base 8. It is immaterial if the etchant destroys the emulsion relief. The lacquer layer is now functioning as the resist. Also the metallic layer functions as an etching-control layer.

Figure 6 shows the completed plate with the emulsion and varnish layers removed.

What is claimed is:

1. A material for use in the art of photomechanical printing including a basic metallic sheet whose surface is plated with a nickel layer suitable for effecting etching control substantially as herein described, such layer supporting a lacquer or varnish layer which in turn supports a colloid layer containing a sensitive silver salt. 20

2. A material for use in the art of photomechanical printing including a basic copper sheet whose surface is plated with a nickel layer suitable for effecting etching control substantially as herein described, such layer supporting a lacquer or varnish layer which in turn supports a colloid layer containing a sensitive silver salt. 25

3. In the art of photomechanical printing, the method of producing a printing plate including the steps of exposing a basic metallic sheet whose surface is plated with a metallic layer suitably composed to effect etching control substantially as herein described, such metallic layer supporting a lacquer or varnish layer which in turn supports a colloid layer containing a sensitive silver salt, developing the silver image, rendering a colloid relief under the selective control of the silver image with formation of bared lacquer or varnish surfaces, rendering a lacquer or varnish relief under the selective control of the colloid relief with formation of bared metallic surfaces, and etching into the metallic base by a suitable agency under the joint selective control of the lacquer or varnish relief and the metallic interlayer. 30

4. In the art of photomechanical printing, the method of producing a printing plate including the steps of exposing a basic metallic sheet whose surface is plated with a nickel layer suitable for effecting etching control substantially as herein described, such layer supporting a lacquer or varnish layer which in turn supports a colloid layer containing a sensitive silver salt, developing the silver image, rendering a colloid relief under the selective control of the silver image with formation of bared lacquer or varnish surfaces, rendering a lacquer or varnish relief under the selective control of the colloid relief with formation of bared metallic surfaces, and etching into the metallic base by a suitable agency under the joint selective control of the lacquer or varnish relief and the metallic interlayer. 50

5. In the art of photomechanical printing, the method of producing a printing plate including the steps of exposing a basic copper sheet whose surface is plated with a nickel layer suitable for effecting etching control substantially as herein described, such layer supporting a lacquer or varnish layer which in turn supports a colloid layer containing a sensitive silver salt, developing the silver image, rendering a colloid relief under the selective control of the silver image with formation of bared lacquer or varnish surfaces, rendering a lacquer or varnish relief un- 75

2,215,128

der the selective control of the colloid relief and with formation of bared metallic surfaces, and etching into the metallic base by a suitable agency under the joint selective control of the lacquer or varnish relief and the metallic interlayer.

5. A material for use in the art of photomechanical printing including a basic metallic sheet

whose surface is plated with a metallic layer selected from the group consisting of silver, nickel and chromium, and suitable for effecting etching control substantially as herein described, such layer supporting a lacquer or varnish layer which in turn supports a colloid layer containing a sensitive silver salt.

CHARLES EDMUND MEULENDYKE.
